UNITED STATES PATENT OFFICE.

A. H. WOODRUFF, OF LANSING, IOWA.

IMPROVED SLIDE-VALVE.

Specification forming part of Letters Patent No. 56,841, dated July 31, 1866.

To all whom it may concern:

Be it known that I, A. H. WOODRUFF, of Lansing, in the county of Allamakee and State of Iowa, have invented a new and Improved Steam-Valve; and I do hereby declare that the following is a full, clear, and exact description thereof, which will enable others skilled in the art to make and use the same, reference being had to the accompanying drawings, forming a part of this specification, in which—

Figure 1 represents a longitudinal vertical section of this invention. Fig. 2 is a horizontal section of the same. Fig. 3 is a longitudinal section of a double-acting valve constructed according to my invention. Fig. 4 is a horizontal section of the same. Fig. 5 is an end view of the same.

Similar letters of reference indicate like parts.

This invention consists in an angular valve which is fitted into an angular seat, one side of which contains the exhaust and the other the steam port or ports, in such a manner that with a valve of comparatively small area large openings for the supply and discharge of the steam are obtained.

It consists, further, in the arrangement of recesses in the exhaust side of the seat or in the steam side, or in both, in such a manner that the pressure of the steam on the back of the valve is partially or wholly balanced and that a full supply of steam is obtained at the beginning of the stroke.

A A' represent two valves, which are of angular form and fitted on corresponding angular seats B B', as clearly shown in Figs. 1 and 2 of the drawings. The seat B is provided with two ports, a b, the port a to admit steam to one end of the cylinder, and the port b to serve as exhaust-port; and the seat B' is provided with corresponding ports, a' b' which serve as supply and exhaust ports, respectively, for the opposite end of the cylinder. The valves are hollow triangular boxes open on those sides which fit on the steam-supply sides of the seats, and perforated with an oblong slot, c or c', on those sides which fit on the exhaust sides of the seat, and the exhaust sides of the valves are provided with projecting flanges or lips d d', the object of which will be presently explained. Furthermore, the steam sides of the seats are furnished with

recesses e e', and the exhaust sides with recesses f f'.

The operation is as follows: A reciprocating motion is imparted to the valves A A' by a rock-shaft or any other similar means, and if said valves arrive in the position shown in Fig. 1 of the drawings the steam-port a' begins to open and steam is admitted to the corresponding end of the cylinder, while the slot c in the valve A passes the edge of the exhaust-port b, thereby opening communication between the ports a and b in the seat B and allowing the steam from that end of the cylinder to exhaust.

By referring to the valve A' it will be noticed that the same, as soon as the port a' begins to take steam, is in such a position that steam passes through the recess e', and also through the recess f' and slot c', to the interior of the same, and consequently the supply of steam is materially increased at the beginning of the stroke, and at the same time the pressure of the steam on the back of the valve is partially or wholly balanced by the steam admitted under and to the interior of the valve. These valves can be readily combined with the reversing-gear described in Letters Patent granted to me December 27, 1864, or any other suitable reversing-gear may be applied to them; and in order to allow of reversing the valves the seats have to be of the proper length, and each seat is provided with two recesses, e or e', and with two other recesses, f or f', as clearly shown in the drawings.

This invention is applicable also to a double-acting valve, as shown in Figs. 3, 4, and 5. In this case the valve is divided into two compartments, A* A'*, and the exhaust side of the valve is provided with two slots, c* c'*; while the angular seat is furnished with two steam-ports, a* a'*; and with two exhaust-ports, b* b'*'. The recesses f'* in the exhaust side of the seat serve merely to relieve the valve of a portion of the pressure. In the position in which the valve is shown in Fig. 3 it just begins to take steam through the ports a'* and to exhaust through the ports a* and b*.

What I claim as new, and desire to secure by Letters Patent, is—

1. The angular valve, either double-acting

or single-acting, in combination with a correspondingly-angular seat, substantially as and for the purpose described.

2. The recesses $f f'$ in the exhaust side of the valve-seat, in combination with the angular valve, substantially as and for the purpose set forth.

3. The recesses $e e'$ in the steam side of the

valve-seat, in combination with the angular valve, substantially as and for the purpose set forth.

A. H. WOODRUFF.
